UNITED STATES PATENT OFFICE.

THOMAS DRUMMOND, OF CHICAGO, ILLINOIS, ASSIGNOR TO JULIUS C. WINTERMEYER, OF SAME PLACE.

BOX FOR CARRYING BOTTLES.

SPECIFICATION forming part of Letters Patent No. 299,060, dated May 20, 1884.

Application filed December 24, 1883. (No model.)

To all whom it may concern:

Be it known that I, THOMAS DRUMMOND, a citizen of the United States, residing at Chicago, in the county of Cook and State of Illinois, have invented certain new and useful Improvements in Bottle-Carrying Boxes or Pop Boxes, of which the following is a specification.

My invention consists of improvements in boxes—such as are commonly used for carrying bottles, especially pop-bottles; and it has for its immediate object to construct the box in such manner as that the false bottom or perforated bottle-carrier can be easily removed or replaced. This object I accomplish in the manner described in the following specification and illustrated in the accompanying drawings, which are made a part of this application, reference being first had to the drawings, wherein 15 the same letter is used in each figure to indicate like parts.

Figure 1 is a view of one side of the box after the same has been cut through the line Y Y; Fig. 2, a plan view of the box, certain 20 parts being shown in dotted lines.

F is the side of the box-frame; B, the end; E, vertical cleats at the end to strengthen the frame; C, horizontal cleats inserted into grooves in the end pieces, and on which rests the perforated false bottom or bottle-carrier. The perforations are seen at X X.

D represents fastenings, which are secured to the inside of the box above the carrier, so as to hold the same in position. These fastenings are secured so as to be easily removable. They may be inserted into grooves in the end pieces of the box, as shown in the drawings, or otherwise, as desired. The carrier is of such size and shape as to exactly fit into the 35 box, and when in position it is secured between the cleats C and the fastening-pieces D.

The box is put together in the usual manner, the cleats C projecting inward, as shown in Fig. 1 of the drawings. The bottle-carrier 40 is then inserted from the top and put in place on the cleats. The fastening-pieces D are then secured in place, and the box is ready for use.

If, for any reason, it should become necessary or desirable to remove the carrier, the fastenings D may be removed and the carrier be 50 taken out.

By substituting a carrier having larger or smaller holes X X the box can be adjusted to hold bottles of different sizes.

I am aware that it is not new to make pop- 55 boxes wherein the carrier is supported on cleats secured upon or against the ends; but in such boxes the full weight of the bottles is thrown upon the nails which secure the cleats, and the boxes are soon destroyed.

I am also aware that it is not new to construct pop-boxes whose ends are composed of two pieces each, a space being left in each end between the pieces to receive the ends of the carrier. In such boxes the ends of the carrier are flush with the outer surface of the ends of the frame, and the carrier must of necessity be made up with the box-frame. It cannot, therefore, of course, be removed without destroying the frame.

It is to overcome difficulties like these that I have made my invention.

I do not claim, broadly, the constructions shown in my drawings and description; but

What I do claim, and desire to secure by Letters Patent, is—

1. The combination of a box-frame having inner grooves on each end, a perforated bottle-carrier, and cleats which rest in the grooves and sustain the carrier.

2. The combination of a box-frame having inner grooves on each end, a perforated bottle-carrier, cleats which rest in the grooves and support the carrier, and fastenings which are secured to the frame above the carrier and 85 serve to hold the same in position.

In witness whereof I have hereunto set my hand, in the presence of two witnesses, at Chicago, Illinois, this 18th day of December, 1883.

THOMAS DRUMMOND.

Witnesses:

F. W. PARKER,
H. KEHRES.
